WINDOW SASH HOLDER

Filed Nov. 23, 1927

Fig. 1.

Fig.

Inventor:

18 John D. Murphy
by Charles Harvey
his Atty.

UNITED STATES PATENT OFFICE.

JOHN D. MURPHY, OF CHICAGO, ILLINOIS.

WINDOW-SASH HOLDER.

Application filed November 23, 1927. Serial No. 235,142.

This invention relates to window sash holders and its principal object is to overcome the tendency for improperly balanced window sash to move up or down from any adjusted 5 position. Another object is to prevent window sash from rattling.

It is well known that some times the sash weights for a window sash are too heavy or 10 too light to properly balance the sash, with the result that if too heavy the sash weights tend to raise the window, particularly if the window sash has a reasonable amount of play 15 in the frame, and if the sash weight is too light the sash tends to fall from any raised position. In accordance with the present invention the sash is held in any position of adjustment in spite of any unbalanced condition of the sash. The invention consists in 20 the novel features hereinafter fully set forth and claimed.

The invention is clearly illustrated in the accompanying drawing, in which:

Fig. 1 is a perspective view of a fragment 25 of a window, showing a simple embodiment of the present invention applied thereto; Fig. 2 is a vertical cross section taken through fragments of the upper and lower sash of the window and illustrating the device in connection therewith and Fig. 3 is a perspective 30 view of one of the devices alone.

Referring to said drawing, which illustrates one embodiment of the present invention, the reference character 4 designates a fragment of a window frame, 5 the upper 35 sash and 6 the lower sash of a window. 7 designates a fragment of one of the sash cords, which leads from the sash 6 over a sash pulley to a sash weight (not shown) as is well understood. If the sash weights are too heavy for 40 either sash, that sash will tend to rise from any position of adjustment, and if too light the sash will tend to fall. To hold the sash in any position of adjustment against rising 45 or falling, due to the improper balancing thereof, I provide a holder 8, for the sash, which in the form illustrated, comprises a length of wire or rod (preferably spring wire) bent into substantially U shape, one of the branches (designated by 9) having an

eye 10 formed on its end and the other branch 50 11 being rounded as at 12. The U bend 13 provides a spring like effect between the two branches 9, 11 whereby their tendency is to spread apart whenever drawn toward each other. If desired the branch 11 may be made 55 considerably longer than the branch 9 and it may be flattened if desired in a plane transverse to the plane of the device. The eye 10 is adapted for the reception of a screw 14, nail or the like for securing the holder to the window frame. 60

In use the holder is secured to the window stop or strip 15 of the frame by the screw 14 at a point adjacent the meeting ends of the sash, with the branch 11 of the holder in 65 pressing engagement with the side rail 18 of the sash, as is clearly illustrated in Fig. 1. The tension of the holder is exerted in pressing the sash against the parting strip 16 of the frame, thereby frictionally holding the 70 sash in any position of adjustment despite the fact that the sash may be overbalanced or underbalanced. Moreover the holder acts to prevent the sash from rattling in case there is considerable play between the sash and the 75 window stop and parting strip.

The holder lies flat against the window stop or strip 15 and occupies very little space and does not interfere with shade or other curtains. If weather strips are used the 80 holder may be placed between the weather strip and window stop or strip 15.

The holder may be provided for the upper sash as well as the lower one and in that case it is secured to the outer window stop or strip 17 in pressing engagement with the outer side of a side of the upper sash (see Fig. 2). In some cases it may be found desirable to employ a pair of holders for each sash, one being secured at each side of the 90 window in pressing engagement with the sash.

While the friction created by the holder is sufficient to hold the sash in any position of adjustment, it does not interfere, perceptibly, 95 with work of raising or lowering the sash, and being made of wire its presence is scarcely noticeable. It can be quickly applied by

unskilled persons to a window which indicates an overbalanced or underbalanced condition of the sash.

I claim as new, and desire to secure by Letters Patent:

As a new article of manufacture, a window sash holder comprising a short length of resilient wire, bent into U shape, one branch being

approximately one half the length of the other and formed with a screw receiving eye 10 at its end whereby it is secured to a window frame with the other branch of the U, in pressing engagement throughout the major portion of its length with the side rail of a window sash.

JOHN D. MURPHY.
